UNITED STATES PATENT OFFICE.

HENRY E. FLOWER, OF PHILADELPHIA, PENNSYLVANIA.

DEVICE FOR LOCKING OR ANCHORING RAILROAD-CARS ON SIDINGS.

SPECIFICATION forming part of Letters Patent No. 680,034, dated August 6, 1901.

Application filed September 27, 1900. Serial No. 31,247. (No model.)

To all whom it may concern:

Be it known that I, HENRY E. FLOWER, a citizen of the United States, and a resident of Philadelphia, in the county of Philadelphia and State of Pennsylvania, have invented a certain new and Improved Device for Locking or Anchoring Railroad-Cars on Sidings, &c., of which the following is a specification.

My invention relates to an improved construction of device for locking or anchoring railroad-cars on sidings, &c.; and my object is to produce a device for this purpose which shall be simple and inexpensive in construction, which can be easily and conveniently carried from place to place, and which can be instantly applied to the rail and locked against removal or being otherwise tampered with by anyone other than the proper persons.

A further object of my invention is to so construct and arrange the parts that the device may be applied to rails of different sizes with equal effect.

My invention consists of the construction and arrangement of parts, all of which will be hereinafter fully described, and particularly pointed out in the appended claims.

In the drawings forming part of this specification, Figure 1 represents a side elevation of a portion of a rail having my invention applied thereto, a portion of the wheel of a car being also shown. Fig. 2 represents a vertical central section thereof, taken on the line X X. Fig. 3 represents a central longitudinal section of a locking-plug by which my device is secured to the rail. Fig. 4 represents a sectional elevation of a key for turning the locking-plug so as to lock or release the anchor.

Similar reference-numerals indicate corresponding parts in all the figures of the drawings.

Referring to said drawings, 1 designates the rail, which may be of any of the ordinary or approved patterns, and 2 represents my improved locking or anchoring device, the same being shown applied to the rail. This locking device 2 is composed of a body portion 3 and downwardly-projecting extensions 4 and 5, of which the former is preferably, but not necessarily, provided upon its inner face with 50 teeth or serrations 6, which are adapted to

impinge the side 7 of the rail 8, and the other extension 5 inclines outwardly toward its lower extremity and is provided with a threaded opening 9 to receive therein a screw-plug 10, which latter is adapted to impinge the 55 opposite side of the rail 8, and thus secure the locking device in place. The lower inner extremity of the extension 4 is provided with a lip 4^a, which fits under the lower edge of the rail, as clearly shown in Fig. 2, and thus prevents that side of the body portion from rising when in place on the rail.

11 designates a vertically-disposed ring or projection, preferably made integral with the body portion 3 and projecting upwardly in a 60 direct vertical plane with the tread of the rail 8 contacts with the periphery of the car-wheel and locks it against further movement. The ring is preferably an open one, as shown, and may be circular in form, or it may be shaped 65 elliptically, as shown in dotted lines, either of which constructions will readily admit of its being grasped by the hand when carrying the device from place to place.

It will be observed by referring to Fig. 1 75 that the ring 11 has formed upon it shoulders or projections 12, adjacent the under face of the body portion 3, and which practically constitute horizontal extensions of said body portion, said extensions being preferably 70 serrated on their under side, so as to grip the tread of the rail with more firmness.

The inner end of the screw-plug 10 is preferably made conical, its apex being intended to lie below the under surface 13 of the tread 85 portion of the rail, so that when said plug has been tightly adjusted the locking device or anchor will be effectively secured against removal. This construction also admits of the adaptation of my invention to rails of smaller 80 dimensions, as will be apparent.

In order to guard against the accidental removal of the screw-plug 10 when my invention is not in use, I reduce its outer end 10^a, as shown in Fig. 2, and correspondingly reduce the opening 9, so as to form an annular flange 9^a, against which the enlarged threaded portion of the plug will bear, and thus prevent its outward displacement.

14 designates a key, which is preferably 100

formed with a hollow elliptical extension 15, adapted to enter an elliptical groove 16 in the screw-plug 10, by which means said plug is turned in one direction or the other in applying my invention to or removing it from the rail.

While I have shown an elliptical key and similar groove therefor in the plug, it is obvious other constructions may be advantageously made; but I prefer the elliptical construction, in that it will be the less easily tampered with owing to the peculiarity of its shape.

Modifications may be made without materially departing from the essential features of my invention, and I reserve the right to make such alterations or changes as may be held to fairly fall within its spirit and scope.

It will be apparent from the foregoing that my invention provides in a simple and inexpensive manner a device which is particularly well adapted for the purposes intended and one which is strong and durable and easily carried from place to place when desired or necessary.

Having thus described my invention, what I claim, and desire to secure by Letters Patent, is—

1. A device for locking or anchoring cars, comprising a body portion adapted to the rail and having a projection thereon disposed in the path of travel of the car-wheel, and means adjustable in said body portion to engage the under side of the tread of the rail for securing said body portion to the rail.

2. A device for locking or anchoring cars comprising a body portion having side extensions thereon and adapted to the rail, said body portion having a projection thereon disposed in the path of travel of the car-wheel and means adjustable in one of said extensions to engage the side of the tread of the rail for securing said body portion to the rail.

3. A device for locking or anchoring cars, comprising a body portion and side extensions, and adapted to the rail, one of said side extensions being provided with teeth or serrations adapted to impinge the side of the rail, and said body portion having a projection thereon disposed in the path of travel of the car-wheel, and means carried by one of said extensions for engaging the side of the rail for securing said body portion to the rail.

4. A device for locking or anchoring cars, comprising a body portion and side extensions, and adapted to fit over the rail, one of said side extensions being provided with a lip adapted to engage the under side of the tread portion of the rail, and said body portion having a projection thereon disposed in the path of travel of the car-wheel, and means adjustable in an extension of said body portion for securing said body portion to the rail.

5. A device for locking or anchoring cars, comprising a body portion and side exten-

sions, and adapted to fit over the rail, one of said side extensions being serrated and further provided with a lip adapted to engage the under side of the tread portion of the rail, and said body portion having a projection thereon disposed in the path of travel of the car-wheel, and means adjustable in an extension of the body portion for engaging the side of the rail for securing said body portion to the rail.

6. A device for locking or anchoring cars, comprising a body portion having a vertically-disposed ring or projection thereon and side extensions adapted to fit over the rail, one of said side extensions being adapted to impinge one side of the rail, and the other of said side extensions being provided with a threaded opening, and a threaded plug adapted to said threaded opening, by adjusting which it is caused to impinge the opposite side of the rail and retain said body portion in place.

7. A device for locking or anchoring cars, comprising a body portion having a vertically-disposed ring or projection thereon, and side extensions adapted to fit over the rail, one of said side extensions being adapted to impinge one side of the rail, and the other of said side extensions being inclined outwardly toward its lower extremity and being provided with a threaded opening, and a threaded plug adapted to said opening, by adjusting which it is caused to impinge the opposite side of the rail and retain said body portion in place.

8. A device for locking cars on sidings, &c., comprising a body portion having a vertically-disposed ring or projection thereon, and side extensions adapted to fit over the rail, one of said side extensions being adapted to impinge one side of the rail, and the other side of said extensions being provided with a threaded opening, a threaded plug for said opening, said plug having its inner end made conical to fit under the lower surface of the tread portion of the rail, and means for turning said plug.

9. A device for locking cars on sidings, &c., comprising a body portion having a vertically-disposed ring or projection thereon, and side extensions adapted to fit over the rail, one of said side extensions being adapted to impinge one side of the rail, and the other of said side extensions being provided with a threaded opening, a threaded plug adapted to said opening, said plug having its inner end made conical so that its apex will fit under the lower surface of the tread portion of the rail, and the outer end of said plug being provided with a groove, and a key adapted to said groove whereby said plug is turned to fasten the body portion to the rail or release it therefrom.

10. A device for locking cars on sidings, &c., comprising a body portion having a vertically-disposed ring or projection and longitudinal serrated extensions thereon, side extensions forming part of said body portion, and adapted

to fit over the rail, one of said side extensions being adapted to impinge one side of the rail, and the other of said side extensions being provided with a threaded opening, a threaded plug adapted to said opening, said plug having its inner end made conical so that its apex will fit under the rail, and the outer end of said plug being provided with an elliptical

groove, and a key adapted to said groove whereby said plug is turned to fasten the body portion to the rail or release it therefrom.
